UNITED STATES PATENT OFFICE.

WILLARD T. WALKER, OF RACINE, WISCONSIN.

LIFTING-JACK.

1,333,645.

Specification of Letters Patent. Patented Mar. 16, 1920.

Application filed September 5, 1919. Serial No. 321,905.

To all whom it may concern:

Be it known that I, WILLARD T. WALKER, a citizen of the United States, residing at Racine, in the county of Racine and State of Wisconsin, have invented certain new and useful Improvements in Lifting-Jacks, of which the following is a specification.

My invention relates to an improvement in a lifting jack, and more particularly to a jack which may be used, for example, in quickly lifting an automobile to change the tires, the rack bar of the jack being adjusted in the standard so that the effective length of these two members will be greater than the distance between the axle and the ground making it necessary to set the jack at an angle under the axle of the vehicle, the lifting operation being performed by pushing the relatively long handle downwardly to the ground which causes the base of the jack to move past center under the axle whereby the load is sustained by the standard and the handle of the jack each acting as a brace for the other. Since jacks of this type are limited to a single lifting movement by the handle, it is essential that the rack bar be properly adjusted in the standard preparatory to the lifting operation. If the rack bar is not high enough in the standard, the load will not be raised high enough and if the rack bar is too high in the standard, the angle of action will be too great to overcome.

The primary object of my invention is to provide an improved jack of this general type of simple and compact construction having means whereby the rack bar may be quickly raised with respect to the standard of the jack to just the proper height preparatory to the lifting operation.

The invention consists in the novel and improved constructions, arrangements and devices to be hereinafter described and claimed for carrying out the above stated object and such other incidental objects as will appear from the following description of a preferred embodiment of the invention which is illustrated in the accompanying drawings, wherein—

Figure 1 is a vertical sectional view of a jack embodying the principles of my invention the handle being broken off;

Fig. 2 is a transverse sectional view taken on the line 2—2 of Fig. 1;

Fig. 3 is a rear elevational view on a re-

duced scale certain parts being shown in section;

Fig. 4 is a side elevational view of the jack in position under the axle of the vehicle preparatory to the lifting movement, and

Fig. 5 is an elevational view of the jack showing the same sustaining a load.

Like characters of reference designate like parts in the several views.

The jack comprises a tubular standard 10 mounted on rollers 11 and provided with an operating handle 12. The base member 13 of the standard preferably comprises a T-shaped casting or pipe fitting the opposite ends thereof being formed with the internal threads 14 which are adapted to be engaged by the threads formed on the inner ends of the stub-shafts 15 on which the rollers 11 are mounted. The vertical bore 16 in the member 13 is provided with internal threads 17 adjacent its upper end which are adapted to engage the external threads formed on the bushing 18. One end of another T-shaped casting or pipe fitting 19 has screw threaded engagement with the bushing 18. A guiding member 20 is screw threaded into the opposite end of the member 19. The rack bar 21 is guided in the standard thus formed by the bushing 18 and the member 20. The member 19 is formed with a laterally extending boss 22 preferably internally screw threaded for the reception of the handle member 12. The upper end of the rack bar is screw threaded into the cap 23. A collar 24 is placed over the member 20 which rests against the top of the member 19. The collar is prevented from turning by the set screw 25 the inner end of which projects into a vertical guideway 26 formed in the rack bar 21. The rack bar is preferably circular in cross-section and is prevented from turning in the standard by the set screw 25. Since the guideway 26 does not extend to the bottom of the rack bar the set screw serves also as a stop to limit the upward movement of the rack bar. The collar 24 is formed with two laterally extending lugs 27 between which a pawl 28 is pivotally mounted on the pin 29. The upper end of the pawl 28 projects through a slot 29a formed in the member 20 and is adapted to engage the teeth formed on the rack bar 21, the pawl normally being held in engagement with the teeth of the rack bar by the spring 30.

95

100

105

110

The rack bar is preferably raised by a spring 31 which is placed inside the rack bar the lower end of the spring seating against the bottom of the base member 13 and the upper end of the spring bearing against the under side of the cap 23. The pawl 28 is preferably formed with a hooked portion 32 which is adapted to hook over a pin on the cap 23, this arrangement being for the purpose of holding the rack bar within the standard when that is desirable. The hook 32 may be pulled out of engagement with the pin 33 by pulling the chain 34, this chain being secured to the outer end of the handle as shown in Fig. 4.

Operation: Assuming that the rack bar has been pushed down into the standard and the hook 32 is in engagement with the pin 33 to hold the rack bar down, the jack 20 is placed under the axle of a vehicle at approximately the angle shown in Fig. 4; the chain 34 is then pulled which disengages the hook 32 from the pin 33 and the rack bar is lifted upwardly into engagement 25 with the axle of the vehicle by the action of the spring 31, as shown in dotted lines in Fig. 4. The chain may then be released and the pawl 28 will be forced into engagement with the teeth on the rack bar by the 30 spring 30 thereby preventing the rack bar from slipping downwardly into the standard. This preparatory adjustment of the rack bar with respect to the standard permits the operator to place the jack at the 35 proper angle under the axle of the vehicle and whatever lost motion there may be between the cap and the axle is taken up by raising the rack bar. The handle of the jack is then pushed downwardly until it 40 touches the ground which movement of the handle causes the jack to pass beyond the center or vertical position. By this movement the load is lifted and is sustained by the standard and the handle of the jack each 45 of these members acting as a brace for the other, Fig. 5 illustrates the position of the jack when sustaining a load. The handle is preferably bent as shown in Fig. 4 so as to more effectively engage the ground.

50 While I have shown and described my invention as applied to a jack in which the rack bar is raised by a spring upon releasing the holding member I do not intend to limit the invention in this respect as it will 55 be obvious that the rack bar may be raised in other ways, the spring arrangement being the preferred one. It will also be obvious that various modifications may be made in the device without departing from the 60 principles of the invention. I do not intend, therefore, to limit the invention to the constructions, arrangements and devices shown and described except only in so far as certain of the appended claims are specifically so limited.

I claim:

1. A lifting jack comprising a tubular standard, a handle rigidly associated with said standard, a tubular member slidably mounted in said standard, a compression spring within and adapted to raise said member with respect to the standard, means adapted to retain said member in the standard against the action of the spring, and means to prevent said member from slipping back into the standard after being raised relative thereto, whereby the jack may be positioned obliquely under the load, said means released and said member, through the influence of said spring, moved into engagement with the load preparatory to the lifting operation. 75

2. A lifting jack comprising a tubular standard, a handle rigidly associated with said standard, a tubular rack bar slidably mounted in said standard, a compression spring within and adapted to raise said rack bar with respect to the standard, means adapted to retain said rack bar in the standard against the action of the spring, and a pawl pivoted to the standard and adapted to prevent the rack bar from slipping back into the standard after being raised relative thereto, whereby the jack may be positioned obliquely under the load, said means released, and said rack bar, through the influence of said spring, moved into engagement with the load preparatory to the lifting operation. 90

3. A lifting jack comprising a tubular standard, a roller pivotally attached to the base of the standard, a handle rigidly associated with said standard, a tubular rack bar slidably mounted in said standard, a compression spring within and adapted to raise said rack bar with respect to the standard, a hook member pivoted to said standard and adapted to retain said rack bar in the standard against the action of the spring, and a pawl pivoted to the standard and adapted to engage the teeth on said rack bar to prevent the rack bar from slipping back into the standard after being raised relative thereto, whereby the jack may be positioned obliquely under the load, said hook member disengaged from said rack bar, and said rack bar, through the influence of said spring, moved into engagement with the load preparatory to the lifting operation. 110

4. A lifting jack comprising a tubular standard consisting of a T-shaped pipe fitting as a base, a second T-shaped pipe fitting disposed so that its straight bore aligns with the angle bore of the first-mentioned fitting, a member connecting the two fittings, a handle rigidly secured in the angle bore of the second-mentioned fitting, a tubular rack bar slidably mounted in said standard, a compression spring within and adapted to raise the rack bar, means to re- 125 130

tain the rack bar within the standard against the action of the spring, and means to prevent backward movement of the rack bar in the standard after it has been raised therein upon release of said first-mentioned means.

5. A lifting jack comprising a tubular standard consisting of a T-shaped pipe fitting as a base, stub shafts secured in the 10 opposite ends of the straight bore of the fitting, rollers on said shafts, a second T-shaped pipe fitting disposed so that its straight bore aligns with the angle bore of the first-mentioned fitting, a member connecting the two fittings, a handle rigidly secured in the angle bore of the second-mentioned fitting, a tubular rack bar slidably mounted in said standard, a compression spring within and adapted to raise the rack 15 bar, means to retain the rack bar within the standard against the action of the spring, and means to prevent backward movement of the rack bar in the standard after it has been raised therein upon release of said 20 first-mentioned means.

6. A lifting jack comprising a tubular standard, a handle rigidly associated with said standard, a tubular rack bar slidably mounted in said standard, a cap secured to 25 the top of said rack bar, a compression

spring in said rack bar interposed between the base of the standard and the cap on said rack bar, a hook member pivoted on said standard adapted to engage and retain said rack bar in the standard against the action 30 of the spring, a pawl pivoted to said standard and adapted to engage the teeth of said rack bar to prevent backward movement thereof in the standard, and a member associated with said handle for disengaging 35 said hook from said rack bar.

7. A lifting jack comprising a tubular standard, a roller attached to the base of the standard, a handle rigidly associated with said standard, a tubular rack bar slidably mounted in said standard, a cap secured to the top of said rack bar, a compression spring in said rack bar interposed between the base of the standard and said cap, a hook member pivoted on said standard 40 and adapted to engage the rack bar and retain it in the standard against the action of said spring, means associated with said handle for disengaging said hook from said rack bar, and a pawl formed integrally with 45 said hook member and adapted to engage the teeth on said rack bar to prevent backward movement thereof in the standard.

WILLARD T. WALKER.
